(57) CLAIM

The ornamental design for a top metal end wall having an easy open score line for a metal container, as shown and described.

DESCRIPTION

FIG. 1 is a perspective view of a top metal end wall having an easy open score line for a metal container and showing my new design;

FIG. 2 is a side elevation view thereof, other side elevation views being the same;

FIG. 3 is a top view thereof; and,

FIG. 4 is a bottom view thereof.

The broken lines in the Figures are for illustrative purposes only and form no part of the claimed design.
